HAIR TREATING OVEN

Burney J. Balmer, Kansas City, Mo.

Application August 28, 1933, Serial No. 687,137

13 Claims. (Cl. 132—36)

This invention relates to hair waving machines, and particularly the clamp and oven assembly which is used to directly apply heat to strands of hair which are wound upon the well known hair-receiving spools, and the primary object of this invention is to provide a unique and novel hair treating oven wherein the hood thereof is positively affixed to the vise in such manner that the jaws of the vise are maintained against accidental displacement during the application of heat and the seal between vise and hood is unbreakably established.

Another object of the present invention is to provide a hair treating oven for permanent wave machines using steam as a heating element having a moisture-absorbing gasket that is formed in a particular manner so as to present a condensate absorbing element within the oven that precludes the collection of moisture at any time. Further specific aims of this invention will appear during the course of the following specification, referring to the accompanying drawing, wherein:

Figure 1 is a side elevation of a hair treating oven made in accordance with this invention.

Fig. 2 is a longitudinal cross section through the same, taken on line II—II of Fig. 1.

Fig. 3 is an end plan view of the completely assembled oven.

Fig. 4 is a vertical, central, cross section through the oven.

Fig. 5 is an enlarged, fragmentary, sectional, detailed view through one end of the oven, showing the specific manner of constructing the clamping element.

Fig. 6 is a top plan view of the vise forming a part of the unique oven illustrating the articulated strips thereof in a separated position.

Fig. 7 is a vertical, central, cross section through the oven with the special gasket for absorbing condensate in place, and,

Fig. 8 is a plan view of the gasket entirely removed from association with the oven and in the blanked-out form.

While Figs. 1 to 5 inclusive illustrate the hair treating oven without the novel gasket associated therewith, it must be understood that the gasket may be applied without altering the structure of the oven in any manner whatsoever and this gasket might be used or not, as the operator deems advisable.

In preparing the hair for a permanent wave, same is blocked off and the vise shown in Fig. 6 applied near the scalp so that the free ends of the hair might be wound around spool 10 which is

rotatably supported by this vise, that comprises a pair of strips 12, each covered by a jacket of resilient material 14 which, when the strips 12 are drawn together as shown in Fig. 4, will grip the strands of hair therebetween to positively preclude slipping. Strips 12 are hingedly secured together at one end by a link 16 and a similar link 18 at the other end of strips 12 supports a manually operable latch member 20 that co-operates with a notch 22 formed in one strip 12 for the purpose of securing together both strips 12 after the hair has been passed therebetween.

In the instance shown, each link 16 and 18 respectively is U-shaped in transverse cross section and at least one wall thereof is provided with a tapped opening 24 for the reception of a hereinafter described screw-threaded clamping element.

Link 16 is likewise provided with a tapped opening 26 for a similar purpose and strips 28 and 30 rigidly secured to the jaws of the vise present tongues 32 and 34 respectively which combine with rims 36 and 38 of spool 10 to rotatably secure said spool in place. Tongue 34 progressively engages detents 39 as spool 10 is rotated and precludes unwinding of the spool after the strand of hair has been tightened thereon. As is customary, a clamping finger 40 is provided on spool 10 so that the ends of the strand of hair being wound might be secured in place before the spool is rotated.

A sheet metal hood 42 is carried by strips 12 and joins with the latter in completely housing spool 10 and its associated parts. This hood 42 must be secured in place with sufficient force to prevent escape of air therefrom because steam is applied to the hair wound upon spool 10 by passing the steam into intake port 44 that is formed through the boss and side wall of hood 42. Another similar boss 46 provides an exit for the steam in order to set up complete circulation and obviously a certain amount of condensation will take place during the operation.

To preclude this condensate from contacting the scalp, a moisture-absorbing gasket 48 is contemplated. This gasket 48 may be made of ordinary blotting paper or similar substance and should be formed as distinctly illustrated in Fig. 8. The gasket is applied before hood 42 is moved to position and underlies the edge thereof. In other words, it is interposed between hood 42 and the resilient material which circumscribes strips 12. Walls 50 are set off on the normally planar gasket 48 between openings 52, one of which is formed through the gasket adjacent each end

thereof as shown, and a longitudinal slit 54 extending centrally along body 48 between openings 52 separates these walls 50 so that they may be extended laterally as shown in Fig. 7 when 5 the gasket is moved to position by causing spool 10 to enter openings 52 and slit 54.

Walls 50 are thereby automatically formed by moving outwardly around a line of bend 56. Notches 58 formed in the ends of gasket 48 allow 10 clearance for the threaded clamping member which effects connection between vise and hoods. The unique manner of interconnecting hood 42 with strips 12 is embodied in the clamping element 60 that has a knurled head 62 preferably 15 formed of fibrous material that is a non-conductor of heat. A screw-threaded shank 64 extends through bearing 66 that is rigid with hood 42 and this bearing permits free rotation of the entire clamping element 60. Shank 64 extends 20 into tapped opening 24 of link 18 and a collar 68 secured intermediate the ends of shank 64 limits longitudinal movement of element 60 in bearing 66.

Openings 70, formed through the walls of 25 bearing 66, are not tapped and the end of shank 64 is tapered as at 72 so that the clamping element 60, one of which is located on each end of hood 42, may be quickly moved to the operative position so that it will draw hood 42 down against 30 gasket 48 or resilient covering 14, as the case may be. Tightening these clamping elements will set up a positive seal between parts of the hair treating oven and when steam is passed through the oven no leakage will occur and a quick dis- 35 assembling may take place merely by unscrewing clamping elements 60. Insulating strips 74 are provided to insure that no objectionable heat will be conducted from the oven to the scalp.

An oven for treating hair that is made in accordance with the foregoing will be found to be 40 positively assembled when the hood is in place. No accidental opening of the vise can occur because the hood and its associated clamping elements will preclude moving apart of links 16 and 18. Any suitable materials might be used 45 in constructing the parts of the oven, but it has been found that rust-resisting metal is best in forming the metallic parts of the oven.

Having thus described the invention, what is 50 claimed as new and desired to be secured by Letters Patent is:

1. A hair treating oven comprising a hair clamping vise; a hood carried by the vise; and clamping elements rotatably carried by the hood and having screw-threaded engagement with a 55 portion of the vise.

2. A hair treating oven comprising a hair clamping vise; a spool carried by the vise; a hood adapted for mounting on the vise; and clamping elements joining vise and hood having screw-threaded engagement with a portion of the vise and being carried for free rotation by said hood.

3. A hair treating oven comprising a pair of hair clamping strips; links joining the ends of said strips to hold the same together; a hood carried by the strips; and clamping elements at each end of the hood having screw-threaded engagement with the said links whereby to draw the hood tightly against the said hair clamping strips.

4. A hair treating oven comprising a pair of hair clamping strips; a link hingedly joining one end of the strips; a latching link releasably joining the other ends of said strips; said links each 75 having a tapped opening formed therethrough;

a hood adapted for mounting on one side of the hair clamping strips when the same are latched together; and a clamping element adapted for screw-threaded engagement with each of said tapped openings respectively, said element and hood serving to secure together the said links when the hood is being held in place. 80

5. A hair treating oven comprising a pair of hair clamping strips; a link hingedly joining one end of the strips; a latching link releasably joining the other ends of said strips; said links each having a tapped opening formed therethrough; a hood adapted for mounting on one side of the hair clamping strips when the same are latched together; and a clamping element adapted for screw-threaded engagement with each of said tapped openings respectively, said element and hood serving to secure together the said links when the hood is being held in place, said clamping elements being carried by the said hood for 85 free rotation about the axis thereof. 90

6. A hair treating oven comprising a pair of hair clamping strips; a link hingedly joining one end of the strips; a latching link releasably joining the other ends of said strips; said links each having a tapped opening formed therethrough; a hood adapted for mounting on one side of the hair clamping strips when the same are latched together; and a clamping element adapted for screw-threaded engagement with each of said tapped openings respectively, said element and hood serving to secure together the said links when the hood is being held in place, said clamping elements being carried by the said hood for 95 free rotation about the axis thereof. 100

7. A hair treating oven comprising a pair of hair clamping strips; a hood adapted for mounting on one side of said strips; clamping elements 105 to removably secure said hood in position; and a gasket of moisture-absorbing material interposed between the said hood and hair clamping strips.

8. A hair treating oven comprising a pair of hair clamping strips; a spool rotatably carried by the strips; a hood adapted for mounting on the strips over the said spool; clamping elements to removably secure said hood in position; and a gasket of moisture-absorbing material clamped 115 between the said hood and said hair clamping strips, said gasket having an upturned wall extending longitudinally along each side respectively of said spool. 120

9. A hair treating oven comprising a pair of hair clamping strips; a spool rotatably carried by the strips; a hood adapted for mounting on the strips over the said spool; clamping elements to removably secure said hood in position; and a gasket of moisture-absorbing material clamped 125 between the said hood and said hair clamping strips, said gasket having an upturned wall extending longitudinally along each side respectively of said spool, said hood having an intake 130 and an exit port formed therethrough whereby to pass steam through the hood as hair is being treated, said gasket adapted to absorb condensate during the treating operation. 135

10. As a new article of manufacture, a gasket 140 for hair treating ovens of the character described having a hair-receiving spool, comprising an initially planar sheet of moisture-absorbing material having opposed wall-forming areas set off thereon, said walls adapted to be extended later- 150

ally from the sheet as the same is moved to position over the spool.

11. As a new article of manufacture, a gasket for hair treating ovens of the character described having a hair-receiving spool, comprising an initially planar sheet of moisture-absorbing material having opposed wall-forming areas set off thereon, said walls adapted to hinge laterally from the sheet along the sides of said spool as the sheet is moved to position over the same.
12. As a new article of manufacture, a gasket for hair treating ovens of the character described having a hair-receiving spool, an initially planar sheet of moisture-absorbing material having a transverse opening formed therethrough adja-

cent each end respectively thereof, and set-off wall-forming areas between said openings.

13. As a new article of manufacture, a gasket for hair treating ovens of the character described having hair-receiving spool, an initially planar sheet of moisture-absorbing material having a transverse opening formed therethrough adjacent each end respectively thereof, and set-off wall-forming areas between said openings, said wall-forming areas being divided from each other by a central longitudinal slit formed through said sheet and extending from one hole to the other.
